UNITED STATES PATENT OFFICE.

LOUIS DOMINIQUE AUGUSTE CASALONGA, OF PARIS, AND GEORGES MIOT, OF VANVES, FRANCE.

DEVICE FOR DRIVING THE BANDS OF ROLLING PLATFORMS.

Application filed May 3, 1922. Serial No. 558,250.

To all whom it may concern:

Be it known that we, LOUIS DOMINIQUE AUGUSTE CASALONGA and GEORGES MIOT, both citizens of the French Republic, residing

5 the former at Paris, 15 Rue des Halles, the latter at Vanves, Seine, 24 Rue d'Issy, France, have invented a new and useful Improvement in Devices for Driving the Bands of Rolling Platforms; and we do

10 hereby declare the following to be a full, clear, and exact description of the same.

This invention relates to a traction device applicable to the translation of platforms of closed circuit; whereby is obtained

15 the essential result that the strain of adherence exerted is quite independent from the weight of the masses to be put into motion and may be as great as is allowed by the resistance of the materials used. The

20 general mean applied according to the present invention to attain the aforesaid result, is characterized by the utilization of the adherence produced upon a metallic band pressed between two rollers strongly pressed

25 against each other, one of which is the driving roller, a band being fastened by any suitable connection to the member constituting the platform to be driven, said member resting, through the medium of

30 wheels, upon suitably disposed rails, so that the traction of this member is thus absolutely independent from any strain of adherence.

One embodiment of the invention is illustrated, merely as an example, by the accompanying drawings, in which:

Figures 1 and 1' are the two halves (to be assembled along the line A—B) of a side-elevation of an element of the mechanism.

40 Figure 2 is a section of the same upon said line,

Figure 3 a view thereof similar to that of Figure 2, but showing the device for supporting the mechanism,

45 Figure 4 a view, taken perpendicularly to the preceding one, of the device shown in Figure 3, and

Figures 5 and 6 are diagrammatical plan views showing the mode of connection of two consecutive elements of the driving band and the manner in which these elements swing relatively to each other when running along a curve.

50 As seen on said figures, the driving mechanism comprises substantially a band 3

formed of consecutive elements and squeezed between a number of pairs of rollers distributed, at suitable intervals, along the whole circuit.

In the drawings are illustrated only two series of pairs of rollers, each of which series comprises two pairs, namely: for the first series, 1, 1^a, 2, 2^a and, for the second one, 1', 1^a', 2', 2^a'. The rollers 1, 1^a, 1', 1^a' are driving-rollers, the rollers 2, 2^a, 2', 2^a' being intended to withstand the pressure exerted by the driving-rollers.

The rollers 2, 2^a (2', 2^a) are mounted loosely upon axes c—d, c'—d' kept stationary in a strong vertical frame 15 resting upon a bed-plate 11 fastened to the ground. The rollers 1, 1^a (1', 1^a), keyed upon the shaft a—b, are driven by any suitable means, for instance by electrical power.

This shaft a—b is supported by a horse-shoe-shaped yoke 7 embracing externally the frame 15 on three faces only.

This yoke may pivot around an axis 14 capable of swing, in turn, around another axis 13 perpendicular to its direction. This arrangement secures a perfect bearing of the rollers against the band 3, whatever be the inclination of the latter.

The pressure upon the band 3 is obtained by the deflection of a blade-spring 12 fastened to the end m of the supporting-yoke 7, such deflection being caused by the rotation of a cam 8 actuated by means of an endless-screw and a worm-wheel 9.

In the case of Figure 3, the spring 12, owing to the position given to the cam 8, has its maximum deflection and transmits its pressure to the rollers 1, 1^a according to the ratio $\frac{om}{om}$, of the lever arms (Figure 95

4), that is to say about according to the ratio $\frac{2}{1}$. It will be understood that, for suppressing the deflection, it suffices to slightly rotate the cam 8 in the direction of the arrow 7', in order that the roller 16 may fall into the depression of said cam.

The endless-screw may be actuated by a small electric motor controlled from a distant central station, from which are controlled all the tractors employed for the translation of the platform.

The vertical frame 15 may pivot around an axis 10 supported by a bed-plate 11 fastened to the ground, this movement enabling

the whole frame to be inclined relative to the vertical.

Each element of the metallic band 3 is connected to a small wagon which constitutes an element of the platform proper.

This connection is realized in the following manner: The band 3 is riveted onto a sheet-iron-beam 6 placed along the axis of the wagon, the four bearing-wheels r of which are each maintained to a bracket fastened to double longitudinal beams riveted upon the two end-cross-beams 5, these two double longitudinal beams and the two end-cross-beams constituting the frame of said wagon.

The elimination of the axles of the wheels r has for its purpose to allow the free passage of the beam 6 and of the driving-band 3. The beam is freely suspended to the frame of the wagon by two trunnions 4, 4' fastened to the middle of the end-cross-beams. The frame of the wagon may thus incline itself relatively to the plane of the traction-beam 6, a condition which is necessary when running along curves of small radius, owing to the super-elevation of the outer rail.

The strain of adherence of the band 3 is transferred to the frame through the medium of the trunnions 4 and 4'. This strain results in a thrust being exerted upon one of the end-cross-beams of the frame, owing to which thrust said frame becomes a driving-frame relative to those which follow it and are coupled with each other and with it.

Each element of the band 3 has substantially the same length as the frame of the wagon which sustains it.

The several elements 3 are independent from each other, as well as from the beams 6 to which they are suspended. They are merely constrained to remain approximately the same distance from the trunnions of the driving shaft $a-b$, the wagons being coupled with each other, like the cars of a railway-train. Assuming that a slight variation take place in said distances, there would result, owing to the possibility given to the frame 15 to pivot around the center 10, no harm whatever as far as the adherence caused by the rollers is concerned. This is, indeed, due to the fact that said frame bears only upon the axis 10 and is suspended to the traction-beam 6 through the medium of the rollers 2, 2', which press constantly upon the band 3, owing as well to the weight of the whole frame as to the reaction due to the tangential strain.

In the case where slight differences of level would exist in the sequence of the wagons which succeed each other for passing between the driving-rollers, the frame 15 would follow these variations by rising or falling owing to the pivotal connection of

the whole around the axis 10. The weight supported by the band 3 may, besides, be balanced up to the required amount by means of a flat spring (not shown) interposed between the frame 15 and the bed-plate 11.

In order to secure the continuity of the traction-strain exerted upon the bands 3, notwithstanding the independence of the band of each wagon relatively to the other, with the series of pairs of rollers 1, 2, 1', 2', illustrated by Figure 1, there has been coupled another series of rollers 1', 2', 1'', 2'' arranged and designed in the same manner as the first one. One of the series is controlled by the other, for instance, through the medium of a chain-gear 17, such as that indicated on Figures 1 and 1' by thick dotted lines. The equality of speeds is thus ensured between the two series of pairs of rollers acting simultaneously on the band; the traction-strain is thereby doubled and said strain transferred from the element 3 to the consecutive one without any abrupt transition.

In order to secure the continuous bearing of the elements 3, notwithstanding their independence, upon the rollers the opposite ends of consecutive elements are respectively concave and convex as illustrated by Figures 5 and 6. It will be readily understood that, owing to said outlines, the foremost element, when about to leave a series of pairs of rollers, is still engaged therewith at the moment when the next element is engaging it. On the other hand, this arrangement enables the consecutive elements to operate within the curves, while preserving, relatively to each other, the same distance, practically as small as it is desired, as separates them when in a straight line.

In the preceding explanations, it has been assumed that the traction-bands 3 were disposed horizontally, but it is obvious that the fundamental principle of the invention would not be altered, if said bands were disposed vertically that is to say at right angles with the plane of the frames of the wagons.

We claim:

1. A traction device for rolling platforms, comprising, a plurality of carriages, a movable band fixed to each of the carriages, a plurality of sets of cooperating rollers, said band being positioned between the rollers of each set, each set comprising a driving, and a pressing roller.

2. A device according to claim 1, an axis positioned at right angles to the direction of motion of the band, a supporting frame pivoted on the axis, said rollers being supported in the frame, whereby the driving rollers can accommodate themselves for change of level of the band.

3. A device according to claim 2, compris-

ing, a horse shoe shaped support embracing the frame on three sides, and connected to the frame by a universal joint, and a shaft in the support, the driving rollers being positioned on the shaft.

4. A device according to claim 3, comprising a tensioning spring fixed to one end of the support for tensioning the rollers, and an adjusting means for the spring, 10 whereby to regulate the pressure between the band and the rollers.

5. A device according to claim 1, said band comprising a plurality of separate elements, having complementary, arc shaped, 15 interfitting end portions, whereby to facilitate passage on curves, and to assure continuous traction of the rollers on the band.

6. A device according to claim 2, said band comprising a plurality of separate elements, having complementary, arc shaped, 20 interfitting end portions, whereby to facilitate passage on curves, and to assure continuous traction of the rollers on the band.

7. A device according to claim 3, said band comprising a plurality of separate elements, having complementary, arc shaped, 25 interfitting end portions whereby to facilitate passage on curves, and to assure continuous traction of the rollers on the band.

In testimony whereof, we have signed our names to this specification.

LOUIS DOMINIQUE AUGUSTE CASALONGA.
GEORGES MIOT.
